CLAIM

The ornamental design for a pin the tail on the donkey party game, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a pin the tail on the donkey party game showing the new design. The design of the pin the tail on the donkey party game is printed on flat material.

FIG. 2 is a front elevational view of the pin the tail on the donkey party game, shown in condition of use; and, FIG. 3 is a front elevational view of the pin the tail on the donkey party game, but shown in another usage state.

The broken lines in the figures illustrate portions of the pin the tail on the donkey party game that form no part of the claimed design.
